212,138

BATH SPONGE HOLDER

John Chudek, Jr., 114 Grand Ave.,
Bellingham, Wash. 98225

Filed Mar. 13, 1968, Ser. No. 10,961

Term of patent 14 years

(Cl. D86—14)

Fig. 1.

Fig. 5.

Fig. 2.

Fig. 4.

Fig. 3.

FIG. 1 is an isometric view of a bath sponge holder showing my new design;

FIG. 2 is a front plan view thereof;

FIG. 3 is a view in side elevation thereof;

FIG. 4 is an end elevational view thereof; and

FIG. 5 is an end elevational view thereof, as viewed from the handle end.

The dotted line showing of the sponge is for illustrative purposes only.

I claim:

The ornamental design for a bath sponge holder, substantially as shown and described.
